UNITED STATES PATENT OFFICE.

JOHN T. WRIGHT, OF GLASGOW, NORTH BRITAIN.

COMBINED PIANO-FORTE AND ORGAN.

SPECIFICATION forming part of Letters Patent No. 225,090, dated March 2, 1880.

Application filed August 15, 1877.

To all whom it may concern:

Be it known that I, JOHN THOM WRIGHT, of Glasgow, in the county of Lanark, North Britain, have invented an Improvement in the 5 Arrangement or Construction of Musical Instruments, of which the following is a specification.

My said invention, which relates to an improvement in the arrangement and construction of musical instruments, consists in combining together in one and the same instrument a separate harmonium or organ and a separate piano-forte, so that the two instruments, each complete in itself, can be played 15 as one instrument and from one key-board, or as two separate instruments, at the will of the performer; and in order that my said invention may be properly understood, I now proceed more particularly to set forth the system, 20 mode, or manner in or under which the same is or may be used or practically carried into effect, reference being had to the annexed sheet of drawings, and to the letters and figures marked thereon—that is to say:

25 Figure 1 illustrates in section with some parts shown in elevation, and Fig. 2 in front elevation, a portion of the musical instrument constituting my said invention.

In carrying out the invention, the harmonium 30 or organ A is placed below the keys of the piano-forte B, and connecting-rods α , or their equivalents, couple the striking mechanism of the piano-forte with the reed-opening mechanism of the harmonium or organ, so that when 35 a note or notes of the piano-forte is or are struck the corresponding reed-valves of the harmonium or organ are opened.

The connecting-rods α may be permanently attached to the keys or striking mechanism of 40 the piano-forte, or to the keys or reed-valve-opening mechanism of the harmonium or organ, and are carried through the key bottom or frames placed between the keys of the piano-forte and of the harmonium or organ, respectively, and through which key bottom or frames the said connecting-rods are individually free to move downward and upward, according as the keys of the piano-forte are struck or released by the performer. The connecting-rods 45 α are preferably provided with cushions of

leather or other similarly suitable material, a , at their ends.

By combining together a piano-forte and a harmonium or organ, as hereinbefore set forth, the tone is endowed with the promptness of the 55 piano-forte, and also with the sustaining character of the harmonium or organ.

When it is desired to play the piano-forte separately, or without also playing on the harmonium or organ, this may be effected by ceasing to operate with the feet the treadles connected to the bellows or blower of the latter instrument; or it may be effected by lowering or raising the latter instrument or its key-board.

To enable the piano-forte and the harmonium or organ to be secured together with their key-boards in the proper position for having like notes struck or sounded simultaneously, a hinge-joint connecting the instruments together is provided at E', and when it is desired to separate the instruments so as to play them individually, the pin or rod passing through the joint is withdrawn through one or both ends of the piano-forte, thereby leaving 70 the harmonium free to be drawn out from under the other instrument; or, in place of this arrangement, a pin projecting from each side of the harmonium may enter into a socket on two guides, which are hinged to the bottom of the 75 piano-forte, and when it is desired to separate the instruments, the harmonium is lifted out of the sockets and gently drawn out.

For the purpose of playing upon the harmonium or organ without also playing upon 80 the piano-forte, (when the instruments are combined,) the keys of the latter instrument may be pressed gently, which gives the effect of a harmonium with a percussion action.

In the combined instrument the various 85 stops of the harmonium or organ are or may be placed below the key-board or on the key-blocks of the harmonium, and pedals are or may be placed on the right and left of the harmonium or organ treadles, which operate, by 90 means of levers, cranks, or other suitable mechanism, upon the loud and soft pedals of the piano-forte, respectively.

In place of combining the piano-forte with a harmonium or organ, as hereinbefore de- 95

scribed, it may be combined in a similar manner with the instrument known as the "harmoniphon," or with other tongued or reed or pipe instruments, for the purpose of producing 5 a like effect.

C represents a rod for raising and supporting the harmonium or organ. This rod is attached to a lever or treadle, D, fulcrumed to the side of the case and arranged convenient 10 to the performer, so that pressure downward upon said lever or treadle will force the harmonium or organ upward and into a position to receive the impact of the connecting-rods x.

Upon the organ being raised a prop or support, F, drops down and aids in holding the instrument up until the release of the treadle 15 D permits the organ to drop down out of connection with the piano.

The treadle or lever D is held in its lowered 20 position by a catch, d, so that it may not be necessary to press upon said lever continuously while playing the two instruments.

By my invention the two instruments are rendered capable of use either alone or separately, and this without impairing either instrument or depriving them of any of the qualities they separately possess, and so that the two instruments may be played together with as little difficulty as one of them.

30 I am aware that it has already been pro-

posed to combine in one case a piano and an organ or other similar wind-instrument. In one instance the operation of the two instruments is regulated by means of a thumb-rod communicating with vertical valve-rods and 35 with forks on the keys. In another device screw-hooks and eyes and rods connect the two instruments together, and are disconnected by means of a longitudinal bar notched its whole length to receive the loops and carry them on 40 the bar, moving backward from contact with hooks connecting the valves of the harmonium.

I do not therefore wish it to be understood that I desire to broadly claim the idea of coupling together two keyed instruments, as that 45 idea, broadly considered, is not new; but

What I do claim, and desire to secure by Letters Patent, is—

In a combined piano-forte and organ or other keyed instrument, the key-connecting rods x, 50 hinge-joint E, lever or treadle D, and suitable supports for retaining the organ in position, substantially as and for the purpose set forth.

In witness whereof I have signed my name to this specification in the presence of two sub- 55 scribing witnesses.

JOHN THOM WRIGHT. [L. S.]
